WIRE DRAWING BLOCK

William H. Sommer, Peoria, Ill., assignor to Key-
stone Steel & Wire Company, Peoria, Ill., a cor-
poration of Illinois

Application April 26, 1934, Serial No. 722,580

4 Claims. (Cl. 205—20)

This invention has reference to the art of metal drawing and it relates particularly to wire drawing blocks such as are used in association with drawing dies for reducing wire rods to wire and the drawn wire to different gauges for different manufacturing purposes.

In the art of drawing wire, wire drawing blocks are used singly in association with a drawing die, and such blocks are sometimes arranged in series with a die for each successive reduction of the wire and guiding means between each block, as for example in what are known as continuous wire drawing machines.

It is well known to those skilled in the use of wire drawing blocks that the greatest source of trouble is the wear of the surface of the blocks themselves. This wear arises from slippage of the wire on the surface of the blocks there being substantially always present particles of scale and other materials which are capable of a high degree of abrasive action. Slippage of the wire upon the surface of the blocks, in the presence of abrasive materials, obviously promotes the formation of grooves in the surface of the blocks to render them unsuitable for practical use, frequently resulting in grooves being formed which tend to cause breakage of the wire; or from hammer blows on the surface of the block which produces indentations in such surface. To meet these conditions it has heretofore been necessary to either replace a drawing block with a new one or to remove the block from the machine for the purpose of machining or reconditioning its surface, which is not only costly but when machining is resorted to renders the machine inoperative for a considerable period of time; or as is sometimes resorted to a wear strip is employed which is removably secured about the surface of the block to be replaced by others as wearing occurs. By the use of my improved wire drawing block these expensive and troublesome difficulties are entirely done away with and a block is provided which has a substantially increased life not heretofore deemed possible and without the use of replaceable wear strips or the necessity for machining or reconditioning the block surface.

The invention has for its principal object to provide a wire drawing block with a wire engaging surface of a degree of hardness which is wear resistant and which will withstand hammer blows and resulting indentations in its surface.

The invention has for a further object a wire drawing block, the surface of which is plated with a material characterized by a high degree of

hardness, that is to say wear resistance and which is frictionless as possible.

An additional object lies in the provision of a wire drawing block made from material having a high degree of mechanical strength sufficient to resist injury through stresses set up as a result of its practical use, which material may have the quality of resistance to abrasion to only a limited degree, and a layer of material having the quality of resistance to abrasion in particularly high degree interposed between the wire and surface of the first mentioned material whereby the block as a whole is made more capable of resisting mechanical injury and abrasive wear.

A further object of the invention is a wire drawing block having a chromium plated surface.

A still further object of the invention is to provide a wire drawing block the surface of which is hardened for a substantial depth and such hardened surface plated or otherwise covered with chromium or other material characterized by a high degree of resistance to abrasion.

In the drawing—

Fig. 1 is a plan view of a wire drawing bench or machine showing wire drawing blocks embodying my invention;

Fig. 2 is a face view of Fig. 1 partly broken away;

Fig. 3 is a sectional view of a wire drawing block;

Fig. 4 is a sectional view through the block, transverse to that shown in Fig. 3, as the same would appear if taken on the line 4—4 Fig. 3, and

Fig. 5 is an enlarged sectional detail showing the body of the block on which the drawn wire is coiled or wrapped, the exterior and interior surfaces of which are hardened to a substantial depth and the exterior hardened surface plated or otherwise covered with chromium or other material having a high degree of resistance to abrasion.

Like characters of reference denote corresponding parts throughout the figures.

For the purpose of showing the application and use of a wire drawing block I have shown in Figs. 1 and 2 a conventional form of continuous wire drawing bench. In these figures I designate the bench proper on which are mounted a plurality of drawing blocks 2, each embodying my invention. There is also provided a take-up block 3. Associated with these blocks are drawing dies 4 and sets of guides 5 and 6. Wire as it is drawn passes successively through the succeeding dies, around the successive drawing blocks, 55

in the manner indicated, and the final draft is coiled or wrapped on the take-up block 3. This is substantially the method employed in wire drawing practice, varying according to special design of bench.

5 In Figs. 3, 4 and 5 I have shown a conventional design of wire drawing block 2, which is subject to many variations, depending on mill practice as well as on the kind and character of work 10 to be performed. It is the wire engaging or wire contacting surface with which the invention is concerned and in the instant showing this surface is designated 7 appearing on a substantially cone body 8 held between heads or plates 9 and 15 10.

15 The wire, following each drawing step, is coiled a plurality of times about each block, as is well understood, and finally coiled on the take-up block. The wire engaging surface of the block 20 is subject to constant wear, the one great source of trouble in wire drawing practice, which the present invention eliminates. This is accomplished by plating or otherwise covering the wire engaging surface of a wire drawing block with 25 chromium or other abrasion resisting material, indicated at 11. The chromium metal may be electrically deposited on the working surface of the block. The surface of the material of the body of the block is preferably hardened to a 30 substantial depth, as indicated at 12, Fig. 5.

35 As is well known, it is common practice in the manufacture of wire drawing blocks to utilize materials, such as steel or chilled iron, having a high degree of mechanical strength, and it would follow that the hardest material would wear longest under the conditions of practical use.

40 However, experience teaches that the hardest and strongest metals available for commercial application, while having ample strength to resist any mechanical stress produced as a result of the use here considered, may not be characterized by a particularly high degree of resistance to abrasion.

45 It is also well known that in the process of drawing many of the common grades of wire there is present on the surface thereof a certain amount of scale, which is characterized by hardness and abrasive qualities, and in the atmosphere and on surfaces adjacent the work there is nearly always present a certain amount of dust containing abrasive materials.

50 Further, as has already been noted, in the process of drawing wire, there is necessarily a certain amount of slippage of the wire on the block while at the same time the contact pressure between the wire and the block may be of considerable magnitude.

55 It is thought obvious that such movement of wire upon the surface of the block, in the presence of abrasive materials, provides an ideal method, if such were desired, of wearing grooves in the block. This result, however, is precisely opposed to the one desired, which is, to prevent deformation of the surface and maintain it in smooth working condition.

60 It is to this end that I provide a layer of material which is particularly characterized by a high degree of resistance to abrasion, interposed between the wire and surface of the body of the block.

65 The material of this layer is selected principally

upon the one characteristic of resistance to abrasion, its mechanical strength and other characteristics being of secondary consideration. Chromium is herein referred to as typical of materials which may be used. Electro-plating 5 would be a convenient method of integration of the materials.

10 In the presently described application we have a wire drawing block consisting of a body member composed of material having mechanical 15 strength characteristics suitable to withstand the various stresses applied in practical use and in addition a layer of material interposed between the wire and material of the block for the purpose of protecting the material of the block from 15 abrasive wear. With the damage from abrasive wear minimized, the material of the block may remain free from injury for an indefinite time.

20 Chromium, as is well known, is characterized in a very high degree by wear resistance and a smooth surface of low coefficient of friction. In its application to the wire engaging surface abrasion is minimized and the life of the block is therefore prolonged indefinitely. Furthermore, machining or reconditioning of the wire 25 engaging surface of the block is eliminated, as well as the use of removable wear strips which have, at times, been resorted to. Obviously, in lieu of chromium other depositable metals having these characteristics may be employed. 30 Therefore, while a preferred embodiment of the invention is shown and described, it is to be understood that this is merely exemplary of the concept herein involved and typifies any equivalent structure by which the improved results 35 outlined may be secured.

35 This hardened surface enables the structure to have ample strength to withstand mechanical stresses and forms a rigid non-deformable support for the overlying highly abrasive material. 40

45 Applicant has redrafted his claims in order to more forcibly present his inventive concept and therefore asks that the present claims be withdrawn and in place thereof the following claims inserted:

45 What I claim is:—

1. A wire-drawing block having a hardened peripheral face to provide a rigid non-deformable supporting surface, and an abrasive resisting plating supported by said face to constitute the 50 wire-engaging surface.

2. A wire-drawing block having a hardened peripheral face, and a chromium plating supported thereon to constitute the wire-engaging surface. 55

3. A wire-drawing block having its periphery hardened to a sufficient depth to withstand mechanical stresses, and an abrasion resisting plating associated therewith to constitute the wire-engaging surface. 60

4. As a new article of manufacture, a wire-drawing block comprising a roll body portion peripherally hardened for a substantial depth and covered by a smooth work facing of relatively high resistance to abrasion, the latter consisting of chromium plating overlying and co-extensive with said hardened body portion, whereby said block is preserved by said cover facing and hardened portion from grooving, indenting, or other damage from excessive strain 65 or shock. 70
